S. W. NELSON

STABILIZER FOR VEHICLES

Filed Sept. 16, 1924

INVENTOR.
Stanley W. Nelson

BY
Carroll P. Griffin ATTORNEY.

UNITED STATES PATENT OFFICE.

STANLEY W. NELSON, OF SAN FRANCISCO, CALIFORNIA.

STABILIZER FOR VEHICLES.

Application filed September 16, 1924. Serial No. 737,984.

To all whom it may concern:

Be it known that I, STANLEY W. NELSON, a citizen of the United States, residing at 2324 24th St., in the city and county of San Francisco, State of California, have invented a new and useful Stabilizer for Vehicles, of which the following is a specification in such full and clear terms as will enable those skilled in the art to construct and use the same.

This invention relates to an equalizer for vehicles which is intended to aid in preventing road shocks from being transmitted to the vehicle frame and passengers.

Another object of the invention is to produce an equalizing or stabilizing mechanism which can be applied to any of the common forms of motor cars, which will aid in preventing side sway of the vehicle body.

Another object of the invention is to provide means whereby the inertia of the vehicle body will itself aid in preventing undue body movements thereby making the car ride easier.

Another object of the invention is to provide means whereby the tendency to move differently of all four corners of the vehicle frame may be equalized and coordinated.

Other objects of the invention will appear as the description proceeds.

An embodiment of the invention is shown in the accompanying drawings in which the same reference numeral is applied to the same portion throughout but I am aware that there may be modifications thereof.

Figure 1 is a side elevation of the vehicle axles and frame with this equalizer applied thereto.

Figure 2 is a front elevation of one of the vehicle axles and the vehicle frame showing the stabilizer applied.

Figure 3 is a side elevation of one of the stabilizers, and Figure 4 is a view in elevation of one of the stabilizers looking at right angles to Figure 3.

The stabilizer has been shown applied to a vehicle having plain axles front and back, but it is, of course, equally applicable to the regular motor car with a live rear axle.

In the drawings the axles are shown at 1 and 2, the springs at 3 to 6 inclusive, said springs being connected to the axles and to the rectangular vehicle frame 7 in any well known manner.

One of these equalizer members is secured

over each spring and each one consists of a bracket plate 8 with two depending lugs 9 and 10 to be secured to the under side of the vehicle frame, four links 11 to 14 and a plate 15 with two lugs 16 and 17.

There is also a rectangular frame consisting of two longitudinal bars 19, 20, and two bars 21, 22 which latter bars are connected to the longitudinal bars at points over each spring.

Each of the links is pivotally connected to a slide as shown at 24 to 27, the pivots being arranged to pass through the axis of the rods 19 to 22.

The links are connected to the axle and frame brackets by the pivot pins 28, 29, the resulting structure representing four different stabilizer members pivoted to the frame and axle in four places each in pairs, and each member is in turn more or less controlled by the other through the rods 19 to 22.

In use the car frame approaches and recedes from the car axle as it passes over inequalities in the road. This causes the links 24 to 27 inclusive to slide along the rods 19 to 22 inclusive, and the frictional resistance to such movement is sufficient to cause the car body movement to be much less rapid and smoother than when travelling over the same road with no means for controlling the springs.

It will also be apparent that the several stabilizers may be used without any connection between each other.

What I claim is as follows, but modifications may be made in carrying out the invention shown in the drawings and in the above particularly described form thereof, within the purview of the invention as defined by the annexed claim:

In a vehicle stabilizer two pairs of connected links, each pair being pivoted to the vehicle body and to the axle respectively and frictional means to control the movement of the other ends of the links whereby the vehicle body movement may be controlled, and rods extending at right angles to each other carrying slides to which the links are connected to control the vehicle body movement.

In testimony whereof I have hereunto set my hand this 5th day of September A. D. 1924.

STANLEY W. NELSON.
